MARBLE GAME TARGET CUP OR SIMILAR
ARTICLE

Merton Elihu Knisley, Milwaukee, Wis.

Application February 25, 1954, Serial No. 29,201

Term of patent 14 years

(Cl. D34—5)

Fig. 1.

Fig. 2.

Fig. 3.

Fig. 4.

Fig. 1 is a top view of a marble game target cup or similar article embodying my new design;

Fig. 2 is an elevational view looking at the front edge of the cup of Fig. 1;

Fig. 3 is an elevational view looking at the opposite edge of the cup of Fig. 1; and

Fig. 4 is a cross-sectional development cut along a circumference through the substantially radial grooves.

I claim:

The ornamental design for a marble game target cup or similar article, substantially as shown.
